UNITED STATES PATENT OFFICE.

HERMAN R. HINTZ, OF MASSILLON, OHIO.

PINCERS.

Application filed March 5, 1921. Serial No. 449,666.

To all whom it may concern:

Be it known that I, HERMAN R. HINTZ, a citizen of the United States, residing at Massillon, in the county of Stark and State 5 of Ohio, have invented a new and useful Pincers, of which the following is a specification.

This invention relates to pliers or pincers and especially to pincers adapted for use by 10 shoe makers and the like for removing lifts from heels.

The objects of the invention are the provision of pincers comprising a pair of jaws provided with staggered teeth, means being provided for adjusting the closing movement 15 of the jaws to limit the same as desired.

With these objects in view, the invention consists in the construction and arrangement of parts hereinafter described and illustrated in the accompanying drawings, it being understood that various changes in the 20 form and details of construction may be made within the scope of the appended claims.

The invention thus set forth in general 25 terms is illustrated in the accompanying drawings forming part hereof, in which—

Figure 1 is a side elevation of pincers embodying the invention,

Fig. 2, an edge elevation of the same,

Fig. 3, an end elevation of the pincers, and

Fig. 4 is a fragmentary edge view of the 35 device showing a modified form of the invention.

A practical embodiment of the invention is illustrated in the accompanying drawings in which similar numerals represent corresponding parts throughout the several 40 views.

The pincers comprise a pair of jaws 1 and 2 provided with the integral handles 3 and 4 respectively, which are hingedly connected together by means of the pin 5. The handle 45 4 may be provided with a tack puller, as shown at 6, if desired, although this feature forms no part of the present invention.

Each of the jaws is provided with the 50 teeth 7, these teeth being preferably staggered, as shown, in order that the teeth of one jaw may project between the teeth of the other jaw when the pliers are closed. It will, of course, be understood that these teeth may not be staggered and need not be 55 of the specific form shown in the drawing,

any well known form of teeth or serrations being adaptable for use upon the jaws.

For the purpose of spacing the teeth upon opposite jaws, when the pincers are in the closed position, means are provided for 60 limiting the closing movement of the jaws, this means being illustrated in the drawing as an eccentric disk 8 mounted upon the handle 4, a rivet 9 being shown as the means for pivotally mounting the disk upon the 65 handle and frictionally holding the same in any desired adjustment.

As shown in Fig. 1, it will be seen that the handle 3 engaging the periphery of the disk 8, prevents further closing movement 70 of the jaws, and as the disk is eccentrically mounted, this movement may be regulated by adjusting the disk. As the disk 8 is frictionally mounted, by means of the rivet 9, the disk will remain in any adjusted position.

In Fig. 4 is shown a slight modification of this construction in which the disk 8^a is mounted upon the screw 9^a, a wing nut 9^b being provided for easily and quickly adjusting the disk to any desired position.

From the above description and the accompanying drawings, it will be seen that pincers are provided which are especially adaptable for use in the repairing of shoes, 85 being particularly designed for removing lifts from heels, the teeth being staggered to allow the same to pass upon each side of a nail, thus preventing damage to the teeth from contact with the nail, and the stop being provided upon one handle to limit the closing movement of the jaws, thus preventing the same from being closed entirely upon a nail.

I claim:

1. Pincers comprising handles pivotally connected together, flat, wide jaws with sharpened edges provided upon said handles and arranged to meet in the same line and a plurality of teeth upon the edge of each jaw.

2. A pair of cobbler's pliers for removing heel lifts and the like comprising a pair of handle members pivoted together and opposed, substantially C-shaped jaws upon the 105 handle members, each jaw terminating in a wide sharp edge arranged to meet the edge of the other jaw in the same line, and a plurality of teeth upon the sharp edge of each jaw.

95

110

3. A pair of cobbler's pliers for removing heel lifts and the like comprising a pair of handle members pivoted together and opposed, substantially C-shaped jaws upon the handle members, each jaw terminating in a wide sharp edge arranged to meet the edge of the other jaw in the same line, and a plu-

rality of teeth upon the sharp edge of each jaw, the teeth upon each jaw being staggered relative to the teeth upon the other 10 jaw.

In testimony that I claim the above, I have hereunto subscribed my name.

HERMAN R. HINTZ.
